DESIGN FOR A COMPACT

Dorothy A. Witt, Wilmette, Ill.

Application February 19, 1945, Serial No. 118,018

Term of patent 3½ years

(Cl. D86—10)

To all whom it may concern:

Be it known that I, Dorothy A. Witt, a citizen of the United States, residing in the village of Wilmette, county of Cook, and State of Illinois, whose post office address is 622 Prairie Avenue, Wilmette, Illinois, have invented a new, original, and ornamental Design for a Compact, of which the following is the specification, reference being made to the accompanying drawing, forming a part thereof.

Fig. 1 is a front view of a compact showing my new design in closed position;

Fig. 2 is an edge view thereof;
Fig. 3 is a view of the side shown in Fig. 1 in open position;

Fig. 4 is a cross sectional view thereof taken substantially on the line 4—4 in Fig. 1; and

Fig. 5 is a rear view of the compact in reduced scale.

I claim:

The ornamental design for a compact, as shown.

DOROTHY A. WITT.
